W. CARDUNER

COMBINATION ELECTRIC FAN AND HEATER

Filed May 18, 1920

UNITED STATES PATENT OFFICE.

WILLIAM CARDUNER, OF NEW YORK, N. Y., ASSIGNOR OF ONE-HALF TO SOL MANDEL,
OF NEW YORK, N. Y.

COMBINATION ELECTRIC FAN AND HEATER.

Application filed May 18, 1920. Serial No. 382,293.

To all whom it may concern:

Be it known that WILLIAM CARDUNER, citizen of the United States, and resident of the city of New York, in the county of New York and State of New York, has invented certain new and useful Improvements in Combination Electric Fans and Heaters, of which the following is a specification.

This invention relates to combination electric fans and heaters.

One of the objects thereof is to provide a practical electric appliance which may be adapted for efficient use either as an electric fan or an electric heater for diffusing heat.

Another object of this invention is to provide a device of the type described with means for adjusting the speed of the fan to correspond to the desired use of the device as a fan or a heater.

A further object of this invention is to provide a device of the above type with means whereby the speed of the fan is reduced to a desired degree simultaneously with the connecting of the heating element to the supply circuit.

A still further object is to provide a device of the type described in which the heating apparatus may be readily detached or removably secured to the fan, and which shall be simple, neat and compact in construction.

Other objects will in part be obvious and in part pointed out hereinafter.

With these and other objects in view, the invention consists in the features of construction, combinations of elements and arrangement of parts which will be exemplified in the apparatus hereinafter described and the scope of application of which will be indicated in the following claims.

In the accompanying drawings, in which is shown one of various possible illustrative embodiments of this invention,

Fig. 1 is a vertical elevation partly broken away of a combination electric fan and heater embodying this invention;

Fig. 2 is a transverse section thereof cut along line 2-2 of Fig. 1;

Fig. 3 is a detailed section in plan cut along line 3-3 of Fig. 2 showing the switch mechanism for adjusting the speed of the fan and connecting the heating element to the supply circuit; and

Fig. 4 is a diagram of one form of suitable electric connections.

Referring in detail to the drawing, 10 indicates a hollow stand on which is mounted the motor 11 for driving the fan. The latter comprises a wire frame member 12 within which operate the veins 13 when driven by the motor. The lead wires 11^a for conducting the current to the motor are carried in a cable 11^b passing through an insulating tube 11^c in the stand. The frame 12 is open at the front as at 14 and opposite this opening is mounted the heating element 15. The latter comprises a ring member 16 on which is wound a suitable high resistance wire 17. This ring member 16 is detachably held as by the screw 17^a on a bracket 18, which is held to the plug members 19, 19' of the male member 20 of an attachment plug 21. Insulating washers are provided for insulating the bracket 18 from the plug member 19, the latter being electrically connected to the heater by means of the conductor 19' while the plug member 19' is connected to the heater through the bracket 18 itself. The female portion 23 of the attachment plug is secured in an extension 24 of the stand 10 and the conducting wires 25, 25' for leading the current to the heating element, issue from the attachment plug into the stand through the opening 26.

The switch mechanism for connecting the electric supply to the heating element on the fan and for reducing the speed when the heater is connected will now be described. Adjacent the bottom of the stand is provided the slot 27 through which operates the switch lever 28 pivoted within the stand as at 29 and adapted to operate a double throw switch 30, for connecting the fan or heater to the electric mains 31, 31' as desired. This double throw switch comprises a pair of switch blades 32, 32' carried by the pivoted lever 28. These switch blades are provided with a head portion 33 having extensions 34, 34' adapted to enter into the jaws of the pairs of contact clips 35, 35' secured within the stand and insulated therefrom as at 36. The usual switch lever 37 is provided for regulating the speed of the fan by the resistances 38, 39. This lever 37 operates through a slot 40 in the stand, is pivoted as at 41 and is provided with a contact head 42 for making contact with the contact

studs 43 on the plate 44. An additional resistance 45 is provided for cutting down the speed of the fan when the heating element is in use as will appear from the diagram 5 of electric connections (Fig. 4).

As will be clear from Fig. 4, when the double throw switch is moved in one direction as for example to the right in that figure, the current is led from the mains 31, 10 31' through the heater 15. The fan is then shunted across the mains and revolves very slowly by reason of the current supplied to the motor being cut down by the resistances 45 in the shunt circuit. When the double 15 throw switch is moved in the reverse direction as to the left in Fig. 4, the circuit through the heater is open and the current supplied through one, both or neither of the resistances 38, 39 to the fan motor, depending 20 upon whether the switch lever 37 contacts with the first, second or third contact studs 43. By the scheme of connections shown, the fan alone may be driven when desired or the heater and fan simultaneously 25 operated but at the same time that the switch is thrown to connect the heater to the supply, a resistance is cut into the fan supply circuit so as to reduce its speed to a desired degree. The slow rotation of the fan 30 will then act to aid in diffusing the heat through the room as will now appear.

It will be noted that the heating element 15 is disposed directly opposite the wide or operating portions of the fan vanes 13, so 35 that the heat from the heating element does not first have to travel up to the active portions of the fan before the heat waves are propelled forward. The heat energy of the heating element is both reflected and 40 propelled by the vanes and is further radiated from the heating element itself. Preferably, the fan vanes for efficient action in connection with the heater may be highly polished so as to provide good reflecting and 45 non-heat absorbent surfaces.

It will thus be seen that there is provided

apparatus in which the several objects of this invention are achieved and which is well adapted to meet the conditions of practical use.

50

As various possible embodiments might be made of the above invention and as various changes might be made in the embodiment above set forth, it is to be understood that all matter herein set forth or shown in the 55 accompanying drawings is to be interpreted as illustrative and not in a limiting sense.

Having thus described my invention, I claim:

1. The combination with an electric fan of 60 an electric heater supported opposite said fan, electric circuits for leading current to said heater and to said fan and automatically operating means for reducing the speed of the fan when the circuit is closed through 65 said heater.

2. The combination with an electric fan of an electric heater disposed opposite said fan, electrically operated motive means for said fan, an electric circuit for said motive 70 means, an electric circuit for said heater, and circuit making and breaking means for said circuits adapted to simultaneously connect said fan and heater to the supply, and automatically operating means for reducing 75 the speed of the fan when the circuit is closed through said heater.

3. The combination with an electric fan of an electric heater supported opposite said fan and an electric motor for driving said 80 fan, and an electric circuit for leading current to said heater, and means for reducing the speed of the motor simultaneously with closing the circuit through said heater, said means including resistance for the motor circuit adapted to be included therein upon 85 closing of the circuit through the heater.

Signed at New York city, in the county of New York and State of New York, this 8th day of May, A. D. 1920.

WILLIAM CARDUNER
